STEREOTYPE PLATE FINISHING MACHINE

Charles L. Ricards, South Plainfield, and Isidor Tornberg, Plainfield, N. J., assignors to Wood Newspaper Machinery Corporation, Plainfield, N. J., a corporation of Virginia

Application September 10, 1946; Serial No. 695,965

16 Claims. (Cl. 90—15)

1 This invention relates to improvements in stereotype plate-finishing machines and especially to an improved machine for milling tension lock-up pockets on the concave side of stereotype plates.

A special advantage of the machine of this invention is that it provides a means for accurately registering the pockets milled on the concave side of the plate with a selected registry index point on the printing surface. The provision of this registering means enables the printer to obtain accurate registry with a series of plates employing the tension lock-up system, for instance in color printing, from the position of the pockets alone.

A further advantage of this invention is that it provides a simpler, low-cost machine for printers doing black-and-white printing only from which the complete registry means are omitted without affecting the pocket milling operation. All parts of the simpler may be standard with those of the more complicated machines.

A further advantage of the invention is its simplicity in attaining the automatic milling of pockets on both sides of the plate with only a single cutter bar in approximately the same time cycle that would be required if separate cutter bars were provided to mill each side.

For a complete description of our invention, reference is made to the accompanying drawings in which:

Fig. 1 is a side elevation partly in section on the central plane of a complete pocket milling and registering machine;

Fig. 2 is an end view of the machine illustrated in Fig. 1;

Fig. 3 is a detail plan view of the lateral register adjustment mechanism;

Fig. 4 is a section taken on the line 4—4 of Fig. 1;

Figs. 5, 6, 7 and 8 are diagrammatic illustrations showing critical cutter positions in a complete cycle of operation;

Fig. 9 is a partial end elevation, partly in section, of a modified form of the machine illustrated in Fig. 1;

Fig. 10 is a section taken on the line 10—10 of Fig. 9;

Fig. 11 is a plan view of the portion of the machine illustrated in Fig. 10; and

Fig. 12 is a plan view on a reduced scale of a larger portion of the machine illustrated in Fig. 9.

Referring now to Figs. 1, 2 and 4, a stereotype plate A is secured to cylinder 1 by plate clamp 2. The cylinder 1 is journalled at each end by

journal extensions 3 and 4 in bearings 3 and 4, respectively, which are rigidly attached to main frame 5. Longitudinal slots extend along the walls of cylinder 1 at X and Y. Cutters 6 are carried on cutter bar 7.

The machine is powered by motor 8 contained within main frame 5 and supported on an adjustable base 9. Power is transmitted from the motor to the driven members of the machine through V-belts driven by motor pulley 10 and driving shaft pulley 11 affixed to shaft 12.

The drive for cutters 6 is provided by bevel gears 13 on shaft 12 which mesh with and drive bevel gears 14 secured to the cutter spindles 15 which are journalled in cutter bar 7. Cutter bar 7 is pivoted in bearings 60 and 61 on main frame 5. Angular motion of cutter bar 7 carrying cutters 6 from X to Y is imparted to it by sliding block 16 pivotally attached to oscillating lever

20 17 and working in radial slot 62 in cutter bar 7. Oscillating lever 17 is attached to shaft 18 which is journalled in bearing 19. Bearing 19 is slidably fitted in journal extension 4 of cylinder 1 and is secured against any movement relative to main frame 5 by its flange end 63 secured to bearing 4 by bolts 63. Shaft 18 carries on its outer end crank member 20, the lever arm 73 of which is actuated by the connecting rod 22 secured to crank 21 by a spring connection 23. Crank 21 in its turn is secured to shaft 24.

Shaft 24 is driven by shaft 12 through the worm reduction gear train 25—26—27—28, reducing its speed so that a single revolution of shaft 24 completes one cycle of the machine. Also secured to shaft 24 at the opposite end from crank 21 is cam 29. Cam follower 32, on the lower end of lever 30, through its engagement with cam 29, imparts a longitudinal motion to cylinder 1 in its bearings 3 and 4. Lever 30 is pivoted to main frame 5 at 31 and is doubly pivotally connected to bracket 33 at its upper end so as to permit bracket 33 to rotate with cylinder 1 about bearing 3. Bracket 33 is slidably carried in journal extension 3 of cylinder 1 and is longitudinally adjustable in relation to cylinder 1 through the adjusting screw assembly 34 controlled by hand wheel 35.

Referring now especially to Figs. 1 and 3, adjusting lever 36 is fulcrumed externally about bearing 4 and engages U-shaped bracket 37 which is secured to cylinder 1 by bolts 67. Adjusting screw 38 engages lever 36 by means of the pierced and threaded pin 39 and is controlled by the dual hand wheels 39, carried by the extension arms 64 fixed to main frame 5.

Returning now to Figs. 1 and 2, gear segment 65 forms a part of crank member 20, making an obtuse angle with lever arm 73, also part of that member. Gear segment 65 engages elongated pinion 42 which is affixed to shaft 41.

Segmental broaches or shavers 40 are secured to shaft 41, which is journalled in cylinder 1 and in brackets 33 and 37. Shaft 41 is rotated by interaction of gear segment 65 and pinion 42 and makes one complete revolution in each direction for each revolution of shaft 24. Segmental shavers 40 are spaced apart along and attached to shaft 41 so that the distance between their cutting surfaces is the finished longitudinal dimension of stereotype plate A between the positioning surfaces C and D, which accommodate longitudinal locating pins on the printing cylinder of a press.

Four registry indicators 43 are provided, adjustable laterally and longitudinally in respect to plate A, on arms 44 which are secured to shafts 45 in tandem so that rotation of shafts 45 will carry the arms 44 at both ends with them. Handles 69 are provided to facilitate this movement of arms 44.

Cylinder 1 is provided with lateral locating pins 46 and 47 and longitudinal locating pins 48 and 49. Clamping band 2 is hinged on one end to lugs 50 secured to cylinder 1 and is locked on the other end by toggle lever 51, also secured to cylinder 1 by lugs 68.

In the modified form of the invention illustrated in Figs. 9-12, inclusive, the outer surface of cylinder 1 is provided with four longitudinal grooves 82 in its surface in the vicinity of the position to be occupied by the four corners of stereotype plate A when clamped thereon. In these four grooves, in the spaced relation to each other and to stereotype plate A shown in Fig. 12, are affixed four blocks 76 by four screws 78 passing through the wall of cylinder 1. Blocks 76 are internally threaded to engage externally threaded adjusting screws 77, which have, at one end, a square portion 83 by which they may be engaged by a wrench and a knurled portion 79 for quick adjustment by hand. The other end of adjusting screws 77 carries a ball head 80 which is held in place in a slideable block 75 by spring clip 81. Slidable blocks 75 are mounted in grooves 82 and contain, at the end opposite the position to their attachment to screws 77, a jaw-shaped opening 84 in which they can be brought into engagement with the edge of stereotype plate A when such a plate is clamped on to cylinder 1 by means of clamp 2.

Push button 52 is provided to start motor 8. Upon completion of one cycle, motor 8 is stopped by a limit switch (not shown) operated by cam 53 which is secured to shaft 24.

Stop screws 54 and 54' on main frame 5 are provided to permit a fine adjustment of the limits of angular travel of cutter bar 7. These stops make contact with and limit the motion of crank member 20. Through action of these stops 54 and 54' spring connection 23 is caused to change the full rotary motion of crank 21 to a reciprocatory motion of crank member 20 through approximately a right angle. Thus oscillating lever 17 and gear segment 65 make two full strokes to one revolution of shaft 24.

A stereotype plate A to be milled is placed on cylinder 1 roughly positioned laterally between pins 46 and 47 and longitudinally between pins 48 and 49. At this time indicators 43 have been moved out of the way by means of handle 69.

Clamping band 2 is then drawn over plate A and securely locked in position by means of toggle lever 51. Indicators 43 are then returned to their operating position as shown in Figs. 2 and 4, it being understood that a predetermined registry index point on the printing surface of the plate has been fixed. Adjustment of cylinder 1, in order to insure that the cutters 6 and shavers 40 operate in precisely correct register with that index point, is now made by means of hand wheel 35 and 39.

Taking up first the adjustment provided by hand wheel 35, it will be seen that adjusting screw 34 threading in and out of cylinder 1 will cause bracket 33 to move longitudinally in relation to that cylinder carrying shaft 41 with it. Hence adjustment of hand wheel 35 will displace segmental shavers 40 with relation to stereotype plate A causing the finished surfaces at C and D, by which plate A is to be located on the press, to be precisely fixed longitudinally with respect to the registry index point on its printing surface, as required.

Turning now to the lateral adjustment provided by the dual hand wheels 39, it can readily be seen that adjustment of screw 38 will displace adjusting lever 36 in its relation to extensions 64 of main frame 5 and, since adjusting lever 36 is in engagement with U-shaped bracket 37 which is fastened to cylinder 1, movement of hand wheels 39 will cause rotation of cylinder 1 in bearings 3 and 4. Thus stereotype plate A is adjusted laterally with respect to the cutting positions of cutters 6, which remain fixed in relation to the main frame 5 by stops 54 and 54'.

The modification of the machine illustrated in Figs. 9-12 provides for an additional adjustment of the selected registry marks on the face of stereotype plate A with respect to registry index pointers 43, of which there are four.

It is apparent that the adjustment provided by hand wheels 35 and 39 depends for completeness upon the precise alignment of the printing impression on the face of stereotype plate A with the geometrical axis of that plate. However, in casting stereotype plates there is often a slight misalignment between the axis of a casting box and the matrix carrying the printing impression. If this misalignment is severe, the plate must be discarded and the matrix realigned in the casting box. If, however, as frequently occurs, this misalignment is a small one, for example, within the distortion permitted by the elastic limit of the material making up the stereotype plate, then much time and labor cost can be saved at no sacrifice of accuracy by distorting the stereotype plate bearing such a misaligned printing impression.

The necessity for such a distortion will be observed by the operator immediately upon placing plate A on cylinder 1 and attempting a complete alignment with all four pointers 43 by use of hand wheels 35 and 39 alone. He will find that at best he can register with only two pointers 43 at once, no matter what combination of lateral and longitudinal adjustment with these hand-wheels he tries.

To overcome this inability to achieve precise registry, he brings jaws 84 of the four slideable blocks 75 into engagement with the edge of stereotype plate A by rapid finger adjustment of adjusting screw 77, as shown in Fig. 10. It will be observed that the shape of Jaws 84 is so selected that the effect of pressure applied by block 75 is not to lift plate A away from the face of

cylinder 1. Having brought the desired blocks 15 into operative contact with plate A, by applying sufficient force to the squared portions 33 of the appropriate adjusting screws 17, the printing surface of stereotype plate A can be distorted until it is in alignment with the geometrical axis of cylinder 1, the plate itself, due to the action of jaws 18, remaining in contact with that cylinder.

It will be observed that this corrective distortion cannot exceed an amount within the elastic limit of plate A or rupture will occur. It will be apparent that when both the distortion adjustment and the ordinary lateral and longitudinal adjustments are all correctly made that the location of the pockets cut by cutters 6 on the inside of plate A will be such that, when plate A is locked onto a printing cylinder by the tension lock-up system, the necessary precise printing registry is obtained.

As can be seen from Figs. 7 and 8, when cutter bar 7 is in either of its cutting positions, cutters 6 will be in milling contact with plate A through longitudinal slots in cylinder 1 at X and Y.

Having thus installed stereotype plate A upon the machine, clamped it in place and adjusted its position with reference to a predetermined registry index point on the printing surface of the plate, let us follow through one complete cycle of operation of the machine.

The motor 8 is started by push button 52. Cutters 6 are brought to cutting speed as shaft 24 begins to turn slowly. As shaft 24 turns, cutters 6 are carried from the starting position shown in Fig. 5 through the position shown in Fig. 6 to that shown in Fig. 7, where they begin to mill pockets at X. It will be observed that the motion of crank 21 on shaft 24 necessary to bring cutter 6 from its position in Fig. 5 to its position in Fig. 7 necessarily brought crank member 20 into contact with limit stop 54 as shown in Fig. 2. This moved gear segment 65 in engagement with pinion 42 and hence caused shavers 40 to move. As shown in Figs. 5 through 7, this movement carried shavers 40 past the ends of plate A and shaved precisely to specification the longitudinal locating surfaces at C and D in proper registry.

During the dwell of cutters 6 in the position shown in Fig. 7, the operation of cam 29 causes cylinder 1 to move longitudinally an appropriate distance for milling the pockets at X the length desired, while stop 54 prevents further rotation of shaft 18.

Shaft 24 continuing to revolve, spring connection 23 now imparts a reversed force to lever arm 73. Crank member 20 now causes shavers 40 to complete a reverse revolution while cutters 6 move to the position shown in Fig. 8 where they commence to mill the pockets at Y. Stop 54 now halts rotation of shafts 18 and 41 again and reverse longitudinal motion is now imparted to cylinder 1 by cam 29 causing the pockets at Y to be milled the desired length. Further motion of shaft 24 now brings crank member 20 out of contact with stop 54 and into the starting position again, at which time cam 53 operates a limit switch (not shown) and stops the machine. Cutters 6 are thus brought out again to the position shown in Fig. 5 and, at the same time, movement of shavers 40 leaves them also in the position shown in Fig. 5. One complete cycle has been achieved, leaving the machine ready to re-commence its cycle upon the insertion of another plate.

As can be seen by inspection of Fig. 1, a simpler and cheaper machine can be provided for sale to users not requiring registry means, by keying 3' to 3 and 4' to 4, thus permitting cylinder 1 to move longitudinally, but not laterally, in relation to main frame 5. Bracket 33 is then fixed rigidly to 3', and hand wheel 35 and screw 34 are omitted. Indicators 43, arms 44 and shaft 45 are omitted. Adjusting lever 36, U-shaped bracket 37, arms 64, screw 38, pierced pin 70 and hand wheels 39 are omitted. Stops 46-47, 48-49 and 54-54' will then provide all the locating and adjusting means necessary for successful pocket milling and positioning area shaving in black-and-white printing.

In either type of machine, main frame 5 is constructed with hopper bottom 71 to receive removable box 72 for collection of all shavings. In this connection, a particular feature of our invention is cutter bar 7, which is journaled in main frame 5 at 60 and 61 and carries shaft 12, with gears 13 and 14, spindles 15 and all the necessary bearings for them inside it. As a result, all these elements are neatly and simply protected from metal particles falling from the milling and shaving operations, and from other dust as well. Access to the inside of cutter bar 7 is provided by removable cover plates 74.

While we have described our invention in terms of the particular machine illustrated in the drawings, it will be understood that many variations of detail can be made therein without departing from the scope of our invention, which we define in the appended claims.

We claim:

1. A stereotype plate-finishing machine comprising a main frame, a cylinder having two longitudinal slots in the walls thereof carried on said frame, means for affixing a stereotype plate to the outer surface of said cylinder, a cutter bar journaled in said frame, a plurality of rotating cutters carried by said cutter bar, means to move said cylinder longitudinally in relation to said cutters, means to bring said cutters into cutting position at each of said slots alternately, and motor means for driving said cutters, said cylinder moving means and said cutter positioning means in timed relation to one another whereby said cutters are brought to cutting speed, moved into cutting position at one of said slots, moved longitudinally a predetermined amount relative to that slot, moved into cutting position at the other of said slots and moved longitudinally a predetermined amount relative to that other slot.

2. A stereotype plate-finishing machine comprising a main frame, a cylinder having two longitudinal slots in the walls thereof carried on said frame, means for affixing a stereotype plate to the outer surface of said cylinder, a hollow cutter bar journaled in said frame, a plurality of rotating cutters carried by said cutter bar on spindles enclosed inside said cutter bar, a shaft journaled inside said cutter bar concentric with the journals holding said cutter bar on said frame, driving means whereby said spindles are driven by said shaft, means to move said cylinder longitudinally in relation to said cutters, means to bring said cutters into cutting position in each of said slots alternately and motor means for driving said shaft, said cylinder moving means and said cutter positioning means in timed relation to one another whereby said cutters are brought to cutting speed, moved into cutting position at one of said slots, moved longitudinally

a predetermined amount relative to that slot, moved into cutting position at the other of said slots and moved longitudinally a predetermined amount relative to that other slot.

3. A stereotype plate-finishing machine comprising a main frame, a cylinder having two longitudinal slots in the walls thereof carried on said frame, means for affixing a stereotype plate to the outer surface of said cylinder, a cutter bar journaled in said frame, a plurality of rotating cutters carried by said cutter bar, a shaft from which said cutters are driven, a countershaft, speed reduction means for driving said countershaft from said shaft, cam means carried by said countershaft for moving said cylinder once in each direction longitudinally in relation to said cutters for each revolution of said countershaft, means to bring said cutters into cutting position in each of said slots alternately and motor means for driving said shaft and said cutter positioning means in timed relation to one another whereby said cutters are brought to cutting speed, moved into cutting position at one of said slots, moved longitudinally a predetermined amount relative to that slot, moved into cutting position at the other of said slots and moved longitudinally a predetermined amount relative to that other slot.

4. A stereotype plate-finishing machine comprising a main frame, a cylinder having two longitudinal slots in the walls thereof carried on said frame, means for affixing a stereotype plate to the outer surface of said cylinder, a cutter bar journaled in said frame, a plurality of rotating cutters carried on said cutter bar, a shaft from which said cutters are driven, a countershaft, speed reduction means for driving said countershaft from said first-mentioned shaft, a crank carried by said countershaft, a stub shaft, a crank member carried by said stub shaft, a connecting rod linking said crank to said crank member, yielding means associated with said connecting rod whereby the distance separating the points of attachment of said crank and said crank member may vary, means for limiting the rotation of said stub shaft to less than a complete revolution, an oscillating lever carried by said stub shaft, a block pivotally fixed on said lever, a radial groove in said cutter bar in which said block is slidably engaged whereby one revolution of said countershaft will cause a two-stroke oscillation of said cutter bar in its journals bringing said cutters into cutting position at each of said longitudinal slots alternately, means to move said cylinder longitudinally in relation to said cutters and motor means for driving said first-mentioned shaft and said cylinder moving means in timed relation to one another whereby said cutters are brought to cutting speed, moved into cutting position at one of said slots, moved longitudinally a predetermined amount relative to that slot, moved into cutting position at the other of said slots and moved longitudinally a predetermined amount relative to that other slot.

5. A stereotype plate-finishing machine comprising a main frame, a cylinder having two longitudinal slots in the walls thereof carried on said frame, means for affixing a stereotype plate to the outer surface of said cylinder, a cutter bar journaled in said frame, a plurality of rotating cutters carried by said cutter bar, means to move said cylinder longitudinally in relation to said cutters, means to bring said cutters into cutting position at each of said slots alternately, shaving means carried by said cylinder for shaving lon-

gitudinal locating surfaces on a stereotype plate affixed to said cylinder and motor means for driving said cutters, said cylinder moving means, said cutter positioning means, and said shaving means in timed relation to one another whereby said shaving means complete their operation while said cutters are brought to cutting speed, moved into cutting position at one of said slots, moved longitudinally a predetermined amount relative to that slot, moved into cutting position at the other of said slots and moved longitudinally in a predetermined amount relative to that other slot.

6. A stereotype plate-finishing machine according to claim 4, a second shaft carried by the cylinder, shaving means carried by said second shaft positioned thereon to shave longitudinal locating surfaces on a stereotype plate affixed to said cylinder, a gear segment carried by the crank member and a pinion affixed to said second shaft engaging said segment.

7. A stereotype plate-finishing machine according to claim 1 in which the main frame includes hopper means beneath all cutters having a receptacle cooperating therewith for the collection of shavings from said cutters.

8. A stereotype plate-finishing machine comprising a main frame, a cylinder having two longitudinal slots in the wall thereof slidably mounted on said frame, means for affixing a stereotype plate to the outer surface of said cylinder, a hollow cutter bar journaled in said frame, a plurality of rotating cutters carried by said cutter bar inside said cylinder, a shaft journaled inside said bar concentric with the journals holding said cutting bar on said frame, means enclosed in said cutter bar for driving said cutters from said shaft, a countershaft, speed reduction means for driving said countershaft from said shaft, cam means carried at one end of said countershaft for moving said cylinder longitudinally on said frame once in each direction for each revolution of said countershaft, a crank carried on said countershaft at the opposite end from said cam means, a stub shaft journaled in said frame, a crank member carried by said stub shaft, a connecting rod linking said crank to said crank member, yielding means associated with said connecting rod whereby the distance separating the points of attachment of said crank and said crank member may vary, means for limiting the rotation of said stub shaft to less than a complete revolution, an oscillating lever carried by said stub shaft, a block pivotally fixed on said lever and a radial groove in said cutter bar in which said block is slidably engaged whereby said cutters are brought into cutting position at and moved longitudinally in relation to each of said longitudinal slots once for each revolution of said countershaft.

9. A stereotype plate-finishing machine according to claim 8, a second shaft carried by the cylinder, shaving means carried by said second shaft positioned thereon to shave longitudinal locating surfaces on a stereotype plate affixed to said cylinder, a gear segment carried by the crank member and a pinion affixed to said second shaft engaging said segment.

10. A stereotype plate-finishing machine comprising a main frame, a cylinder having two longitudinally slots in the wall thereof slidably and rotatably mounted on said frame, means for affixing a stereotype plate to the outer surface of said cylinder, a cutter bar journaled in said frame, a plurality of rotating cutters carried by said cutter bar inside said cylinder, means to move said cylinder longitudinally in relation to

said cutters, index means carried by said frame, means for adjusting the extent of longitudinal motion of said cylinder with respect to said index means, means for adjusting the position of said cylinder about its axis of attachment to said frame in respect to said index means, means to bring said cutters into cutting position at each of said slots alternately, and motor means for driving said cutters, said cylinder moving means, and said cutter positioning means in timed relation to one another whereby said cutters are brought to cutting speed, moved into cutting position at one of said slots, moved longitudinally a predetermined amount relative to that slot, moved into cutting position at the other of said slots and moved longitudinally a predetermined amount relative to that other slot.

11. A stereotype plate-finishing machine comprising a main frame, a cylinder having two longitudinal slots in the walls thereof, journal extensions at either end of said cylinder coaxial therewith slidably and rotatably carried by said frame, means for affixing a stereotype plate to the outer surface of said cylinder, a cutter bar journalled in said frame, a plurality of rotating cutters carried by said cutter bar inside said cylinder, index means carried by said frame for determining the position of said cylinder longitudinally and laterally with respect to said frame, a shaft journalled in said frame coaxially with the journals of said cutter bar, means for driving said cutters from said shaft, a countershaft, speed reduction means for driving said countershaft from said shaft, cam means carried by one end of said countershaft, a lever pivotally affixed to said frame, a cam follower at one end of said lever engaging said cam means, a bracket coaxially rotatably and slidably carried by one of the journal extensions of said cylinder, means for adjusting the longitudinal position of said bracket with respect to said cylinder, pivot means connecting the other end of said lever to said bracket, means to bring said cutters to cutting position at each of said longitudinal slots alternately, an adjusting lever pivoted coaxially about the other of said journal extensions of said cylinder, a second bracket fixed to said cylinder displaced from the axis thereof and cooperating with the lever arm of said adjusting lever, an adjusting screw carried by said frame, a nut on said screw engaging said lever arm, and motor means for driving said shaft and said cutter positioning means in timed relation to one another whereby said cutters are brought to cutting speed, moved into cutting position at one of said slots, moved longitudinally a predetermined amount relative to that slot, moved into cutting position at the other of said slots and moved longitudinally a predetermined amount relative to that other slot.

12. A stereotype plate-finishing machine comprising a main frame, a cylinder having two longitudinal slots in the walls thereof, journal extensions at either end of said cylinder coaxial therewith slidably and rotatably carried by said frame, means for affixing a stereotype plate to the outer surface of said cylinder, a cutter bar journalled in said frame, a plurality of rotating cutters carried by said cutter bar inside said cylinder, index means carried by said frame for determining the position of said cylinder longitudinally and laterally with respect to said frame, a shaft journalled in said frame coaxially with the journals of said cutter bar, means for driving said cutters from said shaft, a counter-

shaft, speed reduction means for driving said countershaft from said shaft, cam means carried by one end of said countershaft, a lever pivotally affixed to said frame, a cam follower at one end of said lever engaging said cam means, a first bracket coaxially rotatably and slidably carried by one of the journal extensions of said cylinder, means for adjusting the longitudinal position of said first bracket with respect to said cylinder, pivot means connecting the other end of said lever to said first bracket, a crank carried on said countershaft at the opposite end from said cam means, a stub shaft journalled in said frame, a crank member carried by said stub shaft, a connecting rod linking said crank to said crank member, yielding means associated with said connecting rod whereby the distance separating the points of attachment of said crank and said crank member may vary, means for limiting the rotation of said stub shaft to less than a complete revolution, an oscillating lever carried by said stub shaft, a block pivotally fixed on said lever, a radial groove in said cutter bar in which said block is slidably engaged, an adjusting lever pivoted coaxially about the other of said journal extensions of said cylinder, a second bracket affixed to said cylinder displaced from the axis thereof and cooperating with the lever arm of said adjusting lever, an adjusting screw carried by said frame, a nut on said screw engaging said lever arm, and motor means for driving said shaft, the profile of said cam means being so disposed that said cam follower makes one complete stroke in each longitudinal direction during a single revolution of said countershaft, said longitudinal motion taking place only during periods when said stub shaft is stationary.

13. A stereotype plate-finishing machine according to claim 12, a second shaft journalled in the cylinder and the first bracket longitudinally slidable with respect to said cylinder and longitudinally fixed with respect to said first bracket, shaving means carried by said second shaft positioned thereon to shave longitudinal locating surfaces on a stereotype plate affixed to said cylinder, a gear segment carried by the crank member and a pinion affixed to said second shaft engaging said segment.

14. In a stereotype plate finishing machine, in combination, a cylinder having longitudinal slots at circumferentially spaced points in the wall thereof, means for clamping a stereotype plate to the outer surface of said cylinder in a position to extend over said slots, a milling cutter within said cylinder, a pivoted support for said cutter having an axis extending longitudinally of the cylinder and means for alternately moving said cutter laterally of the cylinder and outwardly thereof through said respective slots to cut pockets at spaced points in said plates.

15. A stereotype plate finishing machine comprising a cylinder having a clamp extending circumferentially adjacent its cylindrical surface for clamping a stereotype plate between said clamp and said surface and a plurality of adjusting blocks carried by said cylinder and adjustably movable along its surface adapted to engage a stereotype plate thereon near its corners and to impose a distorting stress to it.

16. A stereotype plate finishing machine comprising a cylinder having a clamp extending circumferentially adjacent its cylindrical surface for clamping a stereotype plate between said clamp and said surface, a plurality of slid- 75

11

members carried by said cylinder adapted to engage a stereotype plate thereon near its corners, and screw means carried by said cylinder adapted selectively to press said members into adjustably forceable engagement with such a plate.

CHARLES L. RICARDS.
ISIDOR TORNBERG.
